UNITED STATES PATENT OFFICE.

CHARLES BIGEON, OF CINCINNATI, OHIO.

BED-BOTTOM.

SPECIFICATION forming part of Letters Patent No. 377,368, dated February 7, 1888.

Application filed November 15, 1887. Serial No. 255,186. (No model.)

To all whom it may concern:

Be it known that I, CHARLES BIGEON, a citizen of the United States, residing at Cincinnati, Hamilton county, Ohio, have invented 5 new and useful Improvements in Bed-Bottoms, of which the following is a specification.

My invention relates to spring-beds, and is in the nature of an improvement upon Letters Patent No. 364,469, granted to me June 7, 10 1887. In said patent I described a bed bottom or frame having elevated and fixed head and foot rails and intervening movable side rails supported upon and by pivoted braces secured to cross-braces of the main frame intermediate between the head and foot rails, the 15 whole combined with an elastic web secured to the head, foot, and side rails. As thus constructed the weight of a body upon or near one of the side rails, in depressing the latter, was resisted by the elastic tension of the web, 20 owing to the pivotal angle of the supporting-braces. In such construction the intervening cross-rails of the frame are found to be detrimental, as being inconveniently in the way 25 when the bed is depressed by the weight of a body; and the object of my improvement is therefore, first, to remove this objection, and to this end I employ pivotal supporting-braces arranged diagonally and secured to the end 30 sills of the main frame, thus leaving the main frame entirely open and removing all impediments to the free vertical resiliency of the web.

A further objection to the use of the bed-bottom as formerly constructed lay in the fixed 35 and unvariable resiliency of the bed-bottom, which was not adjustable to the variable weights of individuals. This difficulty, also, I overcome in the present invention by rendering the pivotal engagement of the supporting-braces which uphold the movable side 40 rails adjustable in a vertical plane. By this means the pivotal angle of said braces in relation to the web and side rails may be adjusted so that a greater or less vertical displacement 45 of the bed-bottom will compel a greater or less horizontal expansion of the elastic web, thereby increasing or diminishing the resistance, as required.

The constructive features of my invention 50 are fully illustrated in the accompanying drawings, in which—

Figure 1 is a plan view of the bed complete; Fig. 2, an end view of the bed; and Fig. 3 exhibits a cross-sectional view of the bed.

Referring now to the drawings, A A' B B' 55 designate, respectively, the side and end sills constituting the main supporting-frame of the bed.

a b designate the fixed elevated head and foot rails. 60

c c' designate the movable side rails, and C the elastic web, secured in the manner pointed out in my previous patent.

It will be observed that the main frame is 65 rectangular in form and entirely open, having no cross-braces intervening between the head and foot. The side rails are supported, respectively, by braces D D, preferably metal strips, secured at one end pivotally by a screw to the inside of the movable side rails, c c', and 70 at the other end by movable bolts e e to connecting-bars f f, (preferably of metal,) which connect the head and foot rails to the head and foot sills, respectively. The connecting-bars f f are pierced with two or more apertures, g g, 75 as may be desired, in vertical series, through which the braces D D may be bolted to the connecting-bars. It will be observed that the pivotal angle of the braces D D with the side rails, c c', will be greater or less, as the connection between the braces and the connecting-bars is made at the apertures nearest the sills or the head or foot rails, and a greater or less horizontal outward movement of the side rails obtained, as may be desired. It will 85 also be readily seen that the adjustment may be different upon the opposite sides of the bed, if desired, so as to accommodate the bed to persons of different weights when it is to be occupied by two persons. 90

The side rails are provided with links or chains h h, to prevent too great vertical displacement, as described in my former patent. For the braces D D wooden blocks or boards may be substituted, if desired. 95

Having fully described my invention, I claim and desire to secure by Letters Patent of the United States—

1. In combination with the supporting-frame having fixed head and foot rails, the movable 100 side rails, and the elastic web secured thereto, pivotal braces securing the side rails to bars

connecting the upper and lower sills of the base-frame, and adjustable vertically at their connection with the connecting-bars to regulate the horizontal tension of the web under load, substantially as set forth.

2. The combination of the supporting-frame, fixed end rails, *a b*, movable side rails, *c c'*, the elastic web *C*, bars *f f*, connecting the upper and lower end sills of the bed-frame, and the braces *D D*, adjustable thereon, which connect

the same with and support the movable side rails, substantially as set forth.

In testimony whereof I have hereunto set my hand in the presence of two subscribing witnesses.

CHARLES BIGEON.
